(57) **CLAIM**

The ornamental design for a handlebar for a scooter, as shown and described.

DESCRIPTION

The file of this patent contains at least one drawing/photograph executed in color. Copies of this patent with color drawing(s)/photograph(s) will be provided by the Office upon request and payment of the necessary fee.

1. Handlebar for scooter

2. Handlebar for scooter

1.1 is a front elevation view of a handlebar for scooter embodying our new design in accordance with a first embodiment;

1.2 is a rear elevation view thereof;

1.3 is a left side elevation view thereof;

1.4 is a right side elevation view thereof;

1.5 is a top plan view thereof;

1.6 is a bottom plan view thereof;

1.7 is a top perspective view thereof; and

1.8 is a bottom perspective view thereof.

2.1 is a front elevation view of a handlebar for scooter embodying our new design in accordance with a second embodiment;

2.2 is a rear elevation view thereof;

2.3 is a left side elevation view thereof;

2.4 is a right side elevation view thereof;

2.5 is a top plan view thereof;

2.6 is a bottom plan view thereof;

2.7 is a top perspective view thereof; and

2.8 is a bottom perspective view thereof.
